(57) **CLAIM**

We claim the ornamental design for a detergent container for washing machine, as shown and described.

DESCRIPTION

FIG. 1 is a front perspective view of a detergent container for washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view of the detergent container for washing machine in which a detergent container module for washing machine is provided in broken lines to illustrate an example environment; and,

FIG. 9 is a front perspective view of the detergent container for washing machine in which a washing machine is provided in broken lines to illustrate an example environment. The broken lines in the figures depict environmental subject matter and form no part of the claimed design.
